BUST-CONTOUR PAD

Artince Cooper, Auburn, Ind.

Application October 8, 1945, Serial No. 621,020

2 Claims. (Cl. 2—267)

1

This invention relates to improvements in devices intended to provide substitutional replacement of the contour of a bust which has become disfigured and misshapen as a result following the removal of a breast.

In my endeavor to provide such a device I have considered that not only the deficiency which is due to the absence of the removed breast, but also the deficiencies which are due to subsidence of the bust contour at the lower and frontal portion of the shoulder, and at the regions adjacent the disfigured breast area, and to the subsidence at the region of the axilla or arm pit, should be taken into account.

Upon the above concept, the object of my invention, broadly stated, is to provide a pad device embodying a portion designed to simulate and to substitutionally replace the removed breast, and portions to substitutionally restore symmetry to the adjacent bust regions aforesaid; such device to be of construction and arrangement lending itself to being conveniently applied, and to be comfortably worn. Further aims are to so design the device that it is light in weight, neat and trim in appearance, economical of manufacture, durable and dependable, and capable of alteration as to size, proportions and dimensions in conformity with specific individual requirements.

To the above named ends, my invention is embodied in, and its objects are accomplished by the new construction, combination and arrangement of parts described in the following specification, illustrated in the accompanying drawings, and defined in the claims. For brevity, the integumentary elements composing the reverse side of the pad are referred to as bottom sheets. Those composing the obverse side are referred to as top sheets.

In the drawings—

Figure 1 is a perspective view of my new bust contour pad as it appears in readiness to be applied to use.

Figure 2 is an elevational view in the direction of arrow 2 in Figure 1.

Figure 3 is an enlarged cross section view on broken line 3—3 in Figure 1.

Figure 4 is an enlarged cross section view on the broken line 4—4 in Figure 1.

Figure 5 is an enlarged cross section view on the broken line 5—5 in Figure 1.

Figure 6 is a detail.

Figure 7 is an enlarged cross section view, on the broken line 7—7 in Figure 1.

Figure 8 is a diagrammatic top plan view depicting the form of sheet designed to constitute

2

the bottom or underside of the body-structure (hereinafter called case) of my improved pad.

Figure 9 is a diagrammatic top plan view showing the form of sheet which is designed to constitute the top of said case.

Figure 10 is a diagrammatic top plan view illustrating the form of sheet which is to constitute the bottom portion of the covering or envelope in which the said case is enclosed.

10 Figure 11 is a diagrammatic top plan view showing the form of sheet designed to constitute the top portion of the covering in which the said case is enclosed.

Figure 12 is a diagrammatic top plan view depicting the appearance of the case top-sheet after the dart therein will have been closed.

Figure 13 is a diagrammatic top plan view indicating the appearance of the cover top-sheet after the dart in the forepart thereof will have been closed and said sheet will have been lain upon the said case top-sheet, and its border edges will have been united, except in the area between the points 26 and 28, and after the stuffing will have been inserted into the case through the gap 25 between the sheets thereof (at the area between the points 26 and 28) and after the border edges at said area will have been united.

Figure 14 is a diagrammatic elevational view, taken in the direction of arrow 14 in Figure 13.

30 Figure 15 is a view depicting a bust of form illustrating the sunken condition of the areas affected by the removal of a breast.

Figure 16 is a view indicating the appearance of my new contour pad in position applied to the 35 said bust.

A practical procedure in providing the parts for, and in the producing of a pad according to my invention, the structure of said pad comprising, as it does, a soft stuffed case of the peculiar form 40 and function presently to be pointed out, and which said case is enveloped in a light strong covering including attachment straps, is described as follows.

A ply of flexible textile material such as cotton felting or the like, and which said ply is fashioned to the form as indicated in Figure 8, I designate as the case bottom-sheet 21.

A ply of similar material fashioned to the form indicated in Figure 9 is designated as the case 50 top-sheet 23. The said top-sheet 23 at its forward portion is of enlarged dimensions, its borders 24 at said forward portion being of predetermined contours, and a part of said forward portion being cut away to provide a dart opening having the 55 opposed seam edges 25.

A ply of light strong flexible material such as cotton or batiste is fashioned to the form indicated in Figure 10 and it is designated as cover bottom-sheet 29. A ply of similar material and which is cut to the form indicated in Figure 11, I designate as the cover top-sheet 30. Said cover top-sheet 30 at its forward portion is of enlarged dimensions, the border edges 31 thereof are of predetermined contours and a part of its frontal area is cut away to provide an angular opening having the opposed seam edges 33. The branches of said cover bottom-sheet 29 and of said cover top-sheet 30 include extensions (see Figures 10 and 11) which will presently be referred to. In each of the said case sheets 21 and 23, and said cover sheets 29 and 30, the inboard branch thereof is directed at an oblique angle to a chord 37-37 of the outboard curve of said sheet (see broken lines in Figure 8).

Seam edges 25-25 of the case top-sheet 23 (see Figure 9) are now drawn together and sewn, the forward portion of said sheet thus being transformed in cross section and its border edges 24 being brought to form similar to that of the forward portion of the case bottom-sheet 21. The border edges of the said sheets are then held in registration and sewn together except in the area between the points 26 and 28 (see Figure 12). The case assembly so made as above described is now lain upon the cover bottom-sheet 29.

Preparatory to placing the cover top-sheet 30 in place on top of the said case assembly, the seam edges 33 thereof are sewn together, the forward portion of said sheet being thereby transformed in cross section whereby its border outline is brought to form similar to that of the forward portion of the said bottom sheet 29. The said cover top-sheet 30 is now lain on the said case assembly (and which said case assembly, in turn, is lying on the cover bottom-sheet 29), and its border edges are united (see Figure 13) except in the area between the points 26 and 28, with the border edges of the cover bottom-sheet 29, and the border edges of the case bottom-sheet 21 and the case top-sheet 23, as by sewing in the usual manner by machines adapted for the purposes and whereby the said edges are secured together in thin flattened status. The said sheets are then sewn together along the line 40 which is of the curvature indicated in Figure 13. The matched extensions of the branches of the cover bottom-sheet 29 and cover top-sheet 30 (see Figure 13) are then finished into the form of straps 35 and 36 as by suitably hemming their edges. Fasteners for the ends of said straps are preferably of the hook-and-eye type, same being applied in the manner as indicated in detail in Figure 6.

Stuffing which consists of flocculent material such as kapok is applied through the gap at the unbound portions of the case bottom sheet 21 and the case top-sheet 23, between the points 27 and 26, and is worked into place whereby the space between said sheets at their forward portions (bounded by the stitched line 40) will have been filled. Similarly, stuffing is then applied through the gap at the unbound portions of said sheets between the points 27 and 28 (see Figure 13) and is worked into place whereby the space between their trunk or median portions and branch portions will have become properly filled. The structure now is of the appearance in plan as indicated in Figure 13; and in elevation, as indicated in Figure 14, its forepart being conoidal and with underside slightly convex; and the

trunk and branches of the structure being bi-convex in cross section, the distal portions of said branches being of thinned leaf-like formation. Completion of the binding of the border edges of the structure consists of sewing said edges in the manner above indicated, at the area between the points 26, 27 and 28 (see Figure 13).

The several parts constructed, arranged and combined as just described constitute a pad of completed form as indicated in the plan view Figure 13, and in the perspective view Figure 1 and wherein the ends of the straps 35 and 36 are in the connected status. Curviform in plan; and bifurcated, posterior branches thereby being provided, the pad is of form to be applied to the sunken bust areas 44, 45, 46, 47 and 48 (see Figure 15) and in the position indicated in Figure 16.

The surface contour of the convex underside 49 of the conoidal bulge or protuberance 50, and the surface contour of the convex underside 51 of the median portion or trunk 52, and the surface contours of the undersides 53 and 54, of the branches 55 and 56 respectively, of said pad, are such that the pad readily lends itself to be seated in fitting engagement with the aforesaid affected bust areas. And the contours of the obverse surfaces of the conoid 50, trunk 52, and branches 55 and 56 of the pad supply contours substitutional of and approximative to the lost natural contours of said bust. Thus while the conoid, resting as it does at the affected area 44, constitutes a substitutional breast; the fillet 88, the trunk portion 52, branch 55 and branch 56 resting, as they do, at the areas 45, 46, 47 and 48, respectively, of the bust, constitute substitutional replacements for the lost natural contours.

The fillet 88, inner margins of the branches 55 and 56, and the straps 35 and 36 which will have been suitably adjusted, provide an arm-scye 40 whereby the user is enabled to conveniently apply the pad snugly to place. The conventional corset or brassière 61 is then arranged, the ends thereof being brought about in the usual manner and fastened in the back. The conoid 50 of the pad will have been received within the pocket of the brassière, where it rests in correct relation to the bust form.

The device of course may be made in right-hand pattern, as well in the left-hand pattern shown, and it is of utility in instances where the bust deficiencies are incident to the removal of either one or both of the breasts. The inner portion of the base of the conoid 50 being defined by the stitched line 40, a modification for obtaining more or less fullness of form of the conoid involves only an obvious change in the form of the dart 53 and of the border edges of the fore portions of the case top sheet and the cover top sheet. The procedures in making my improved pad may be varied in conformity with the facilities available and requirements as to quantity.

It will be understood that the exemplification of my invention given here is typical, and that alterations and modifications may be made without departing from the principle or spirit of the invention or sacrificing any of its advantages.

What I claim as my invention is:

1. A bust contour pad the integument thereof consisting of opposed soft flexible sheets each curviform in plan and bifurcated, the inboard branch of each of said sheets being directed at an oblique angle to a longitudinal chord of the outer curve of said sheet, and each of said

branches having a flat flexible extension adapted to be interconnected at their outboard ends, the fore part of one sheet being semicircular in plan and the forepart of the other sheet being of expanded formation in plan and having a dart opening, and the borders of said fore part being of predetermined curvatures, said sheets being secured together along a curved line extending rearwardly from the basal portion of said inboard branch and thence forwardly to the opposite edge of said combined sheets, and the opposed edges of said dart opening being united, stuffing applied between said sheets at their fore parts to distend the fore part of the last named sheet into the form of a conoid, and stuffing applied between the sheets at their trunk and branch portions to distend same to biconvex formation longitudinally and transversely, and the borders of said sheets being united, substantially as described and shown.

2. A bust contour pad consisting of a pair of soft flexible textile sheets curviform in plan and bifurcated, the inboard branch of each of said sheets being directed at an oblique angle to a chord of the outboard curve of said sheets, the fore part of one sheet being semicircular in plan and the forepart of the other of said sheets being of expanded plan formation and having a radial dart therein, a pair of soft flexible textile sheets that are similar to and which enclose the

5 first named pair of sheets, the branches of the last named pair of sheets including flat flexible extensions adapted to be interconnected at their outboard ends, all of said sheets being secured together along a curved line extending rearwardly from the forward portion of the base of said inboard branch thence forwardly to the opposite edge of said combined sheets, stuffing applied between the first named sheets at their foreparts 10 to distend same into the form of a conoid, and stuffing applied between said first named sheets at their trunk and branch portions to distend same to biconvex formation, and the borders of said combined sheets being united, substantially as shown.

15 15 ARTINCE COOPER.
